UNITED STATES PATENT OFFICE.

JOHN F. LINDBERG, OF CHICAGO, ILLINOIS.

ELECTRIC SWITCH.

Application filed April 8, 1922. Serial No. 550,895.

To all whom it may concern:

Be it known that I, JOHN F. LINDBERG, citizen of the United States, residing at Chicago, in the county of Cook and State of Illinois, have invented a certain new and useful Improvement in Electric Switches, of which the following is a full, clear, concise, and exact description.

My invention relates to electric switches and is of particular utility when embodied in those switches that are employed in the operation of stop lights upon the backs of automobiles, though the invention is not to be restricted to this use.

The invention has for its general object the provision of a simplified construction and assembly of the switch parts. In the switch there is employed a holder having two connected parts that are preferably angularly related walls, one wall desirably constituting a guide wall and the other an abutment wall. A mounting block of insulation is assembled with the holder at the end thereof which is remote from the abutment wall. A contacting leaf spring, a contact bar, and a retractile leaf spring are simply formed and conveniently arranged in combination with the holder and the mounting block. The mounting block is formed with a slit that receives the contacting leaf spring, this spring being formed with offset portions to obstruct its movement in the slit of the block, the contacting end of the contacting leaf spring being between the mounting block and the abutment wall. There is also a reciprocable contacting bar that desirably has an offset portion between the mounting block and the contacting end of the leaf spring from which contacting end the offset portion of said bar is normally separated. A retractile leaf spring of U-form is desirably employed, this retractile spring having one side in engagement with the abutment wall and its other side coupled with the contacting bar. A switch thus formed is simple in construction and easy to assemble.

The invention will be more fully explained in connection with the accompanying drawing in which Fig. 1 is a view in sectional elevation on line 1-1 of Fig. 2, a mounting for the switch being illustrated and there being also shown the assembly of the switch with an operating lever such as a brake lever of an automobile; Fig. 2 is a sectional view on line 2-2 of Fig. 1; Fig.

3 is a perspective view of a container for switch parts and which is inclusive of the angularly related walls hitherto described; Fig. 4 is a view in perspective illustrating the component parts of the switch, other than the container, in perspective and in separated relation; and Fig. 5 is a sectional view on line 5-5 of Fig. 1.

Like parts are indicated by similar characters of reference throughout the different figures.

The switch illustrated is inclusive of a box having a back wall 1, side walls 2, 3 and 4 and a cover 5, this box constituting a holder for the switch and the walls 2 and 3, in particular, constituting elements which co-operate with the switch, the wall 2 serving as a guide for the reciprocable contacting bar and the wall 3 serving as an abutment for the spring that restores the contacting bar to open circuit position. A mounting block 6, formed of insulating material, is at the end of the holder which is remote from the abutment wall 3, this mounting block being along side of the guide wall 2 and also constituting, in effect, a wall of the box to complete the closure thereof when the cover 5 is in position.

The mounting block has a slit 7 formed therein in which a leaf spring 8 is received. This leaf spring has offset portions 9 and 10 which correspond to the width of the mounting block and prevent the spring from moving in the slit longitudinally. The contacting end 11 of the spring 8 intervenes between the mounting block 6 and the abutment wall 3. A preferably rigid reciprocable contacting bar 12 has one end or portion within the space 13 formed in the mounting block and intervening between the mounting block and the guide wall 2. This reciprocable contacting bar is provided with an offset portion 14 of V form, the left hand side of the V portion of the bar serving to engage the mounting block to limit the extent to which the other side of this offset portion 14 may be removed from the contacting end 11 of the spring 8.

The bar is a circuit terminal, its offset portion 14 constituting a contact which is complementary to the contact 11 and is engageable with such contact 11 when moved to the right and away from the block 6. A retractile leaf spring 15 is of U-form, the right hand side of this spring engaging the wall 3 that serves as an abutment for the

spring. The left hand side of the retractile spring is suitably assembled with the contact bar 12, there being illustrated a lug 16 which is struck from the bar 12 and against which the retractile spring presses in a direction to engage the offset portion 14 of the contacting bar with the block 6 and to remove this offset portion from the contact spring 11.

10 A space 17 intervenes between the adjacent ends of the angularly related walls 2 and 3 through which the contact bar 12 projects for connection with the device that is to operate the switch. As illustrated, the contact bar is formed with a tongue 18 which is projected through a hole through the insulating plate 19 into engagement with which plate said tongue is clinched. When the switch is to be closed the contacting bar 12 is moved to the right and when the switch is employed in a stop light signal the means for actuating the switch may be inclusive of a spring 20 which connects the insulating bar 19 with a brake pedal 21.

15 If desired, there may be employed an insulating block 22 for closing the slit 7 to obstruct sidewise movement of the spring 8. There may be also employed the cover 5 for completing the enclosure of the interior parts of the switch. A bolt 23 may be employed for assembling the block 6 with the switch holder and for securing the block 22 in place. This bolt, in conjunction with another bolt 24, may also serve to hold the cover 5 in position, these bolts passing through suitable holes in the cover and the back wall 1 of the holder.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a switch, the combination with a holder having two angularly related walls, one of these walls constituting a guide wall and the other an abutment wall; of a mounting block of insulating material assembled with the holder at the end thereof remote from said abutment wall and alongside of said guide wall from which it is spaced apart to form a guideway, said mounting block having a slit formed therein; a leaf spring contact element inserted in the slit in said block and formed with offset portions to obstruct its movement along the slit, said leaf spring having its contacting end between the mounting block and the abutment wall; a reciprocable contacting bar having a portion within the space between the mounting block and the guide wall and formed with an offset por-

tion between the mounting block and the contacting end of the leaf spring from which contacting end the offset portion of said bar is normally separated; and a retractile leaf spring of U-form having one side in engagement with the abutment wall and its other side coupled with said bar, there being a lug struck from the bar and having engagement with said leaf spring which serves to restore the bar to circuit opening position with the offset portion of the bar against said block.

2. In a switch, the combination with a holder having two angularly related walls, one of these walls constituting a guide wall and the other an abutment wall; of a mounting block of insulating material assembled with the holder at the end thereof remote from said abutment wall and alongside of said guide wall from which it is spaced apart to form a guideway, said mounting block having a slit formed therein; a leaf spring contact element inserted in the slit in said block and formed with offset portions to obstruct its movement along the slit, said leaf spring having its contacting end between the mounting block and the abutment wall; a reciprocable contacting bar having a portion within the space between the mounting block and the guide wall and formed with an offset portion between the mounting block and the contacting end of the leaf spring from which contacting end the offset portion of said bar is normally separated; and a retractile leaf spring of U-form having one side in engagement with the abutment wall and its other side coupled with said bar.

3. In a switch, the combination with a holder having an abutment; of a mounting block of insulating material assembled with the holder at the end thereof remote from said abutment, said mounting block having a slit formed therein; a leaf spring contact element inserted in the slit in said block and formed with offset portions to obstruct its movement along the slit, said leaf spring having its contacting end between the mounting block and the abutment; a reciprocable contacting bar formed with an offset portion between the mounting block and the contacting end of the leaf spring from which contacting end the offset portion of said bar is normally separated; and a retractile leaf spring of U-form having one side in engagement with the abutment and its other side coupled with said bar, there being a lug struck from the bar and having engagement with said leaf spring which serves to restore the bar to circuit opening position with the offset portion of the bar against said block.

4. In a switch, the combination with a holder having an abutment; of a mounting block of insulating material assembled with

the holder at the end thereof remote from said abutment, said mounting block having a slit formed therein; a leaf spring contact element inserted in the slit in said block and 5 formed with offset portions to obstruct its movement along the slit, said leaf spring having its contacting end between the mounting block and the abutment; a reciprocable contacting bar formed with an offset 10 portion between the mounting block and the contacting end of the leaf spring from which contacting end the offset portion of said bar is normally separated; and a retractile leaf 15 spring of U-form having one side in engagement with the abutment and its other side coupled with said bar.

5. In a switch, the combination with a holder having an abutment; of a mounting block of insulating material assembled with

the holder at the end thereof remote from 20 said abutment, said mounting block having a slit formed therein; a leaf spring contact element inserted in the slit in said block and formed with offset portions to obstruct its movement along the slit, said leaf spring 25 having its contacting end between the mounting block and the abutment; a reciprocable contacting bar formed with an offset portion between the mounting block and the contacting end of the leaf spring from which 30 contacting end the offset portion of said bar is normally separated; and a retractile spring for placing the contacting bar in open circuit position.

In witness whereof, I hereunto subscribe 35 my name this 20th day of January A. D., 1922.

JOHN F. LINDBERG.
